IGNITION APPARATUS

Kenneth A. Harmon and Terrence G. Louis, West Springfield, Mass., assignors to Wico Electric Company, West Springfield, Mass., a corporation of Massachusetts

Original application June 15, 1935, Serial No. 26,726. Divided and this application October 11, 1935, Serial No. 44,566

5 Claims. (Cl. 123—148)

This invention relates to an improved ignition apparatus for internal combustion engines.

This application is a division of our application filed June 15, 1935 under Serial No. 26,726.

5 The invention is capable of general application. It is suitable for use in automobiles, trucks, tractors, motor boats, airplanes and stationary power plants, and so forth. A typical use is in connection with an automobile and such use will suffice as an illustrative example to show the advantages and utility of the invention.

The now prevalent type of ignition apparatus used in automobiles consists of an induction coil, deriving its current from the storage battery, 15 which also supplies current to the starting motor used to crank the engine. This so-called battery ignition system has several disadvantages. An inherent weakness in such a system is that spark current diminishes as the engine speed increases and, on the higher speeds, decreases to such an extent that the effectiveness of the spark is seriously impaired. Such action occurs because magnetic flux can be built up in the core of the induction coil only during the intervals 20 when the breaker points are closed, and the time length of these intervals diminishes as the engine speed increases. And these intervals at the very high speeds are not sufficiently long to enable the magnetism to build up in the core of the induction coil to the same degree that it can in the longer intervals available on slower engine speeds. Another disadvantage of such system is that it is difficult, in extreme cold weather, to 25 secure an effective ignition spark. The difficulty here is that the heavy load imposed on the starting motor in turning over the cold engine, results in a heavy current being drawn from the battery, whereby there is a severe drop in battery voltage. If, for example, the battery voltage 30 drops down to 2 or 3 volts, the current in the primary of the ignition coil will be seriously reduced below the normal value obtained under a normal voltage of say 6 volts. A further disadvantage of the battery ignition system is the 35 relatively heavy current consumption. Typical battery-ignition coils draw 5 to 6 amperes on starting of the engine (assuming normal battery voltage) and during running of the engine the current consumption is around 4½ amperes for 40 the lower speeds and diminishes on higher speeds.

This current consumption is not, of course, a constant load and occurs only during the times when the breaker points are closed. However, in battery-ignition systems the effort is to keep the breaker points closed as long as possible, because the longer they are closed the greater is the flux that can be built up in the core of the induction coil. In typical battery-ignition systems the breaker points will be closed about 70% of the time during which the engine is in operation, so that for the greater part of the time there is this heavy current draw. A further disadvantage of such systems is the relatively rapid wear of the breaker points due to the destructive action of the arcing between the points when 10 they open,—such action increasing as the current flow increases.

The other type of ignition system, formerly used on automobiles but now generally abandoned, is the magneto type. The weakness of 20 this system is the absence of an effective spark on starting. But the magneto has a very important characteristic, which makes it most desirable for the modern automobiles operating at very much higher speeds than heretofore. This characteristic is that the effectiveness of the spark increases as the engine speed increases. This same characteristic accounts for the disadvantage of the magneto for ignition on starting but, if this 25 disadvantage can be overcome, then the magneto offers the best solution for securing effective ignition on the very high engine speeds now being used.

The apparatus of this invention combines both 30 of the aforesaid types of ignition, operating on the battery-energized induction coil principle on starting and on the magneto principle for normal running. Attempts have been made heretofore to combine in an ignition apparatus both the 35 stated types of ignition but, in no case, so far as we are aware, has the problem been solved completely and effectively, so as to be followed up by a commercial development such as to render 40 available a commercially satisfactory ignition apparatus combining the advantages of both the 45 aforesaid systems, notwithstanding the need which has existed and is existing for an apparatus of this sort.

This invention has for its general objects to 50 provide an ignition apparatus which will produce

a much better spark on starting of the engine than the conventional battery ignition system and which will produce an effective spark even under unfavorable conditions, such as that of a 5 partially run down battery or that where there is a heavy drop in the battery voltage due to a heavy withdrawal of current by the starting motor in cranking the engine in cold weather; which will produce a much better spark than the conventional battery-ignition system on extremely 10 high engine speeds; in which a reduction in the wear on the breaker points may be effected because of the substantial reduction in current flow during medium speeds of engine operation; and 15 in which the aforesaid results of better ignition are effected by a more efficient utilization of the battery current with a substantial saving in current over the conventional battery-ignition system and thus a lessened drain on the battery. 20 The invention also has for an object the provision of an ignition system, operating on the battery-energized induction coil principle for starting and at other times on the magneto principle, wherein the same primary and secondary 25 coils are utilized for operation on the induction coil principle as well as on the magneto principle,—the arrangement being characterized in that the primary coil has a much less resistance than the usual primary of an induction coil and is 30 purposely designed to produce good sparking at low engine speeds on the magneto principle of operation,—such primary coil because of its low resistance also enabling an adequate flow of current through it from a partially depleted battery, 35 or one subjected to a heavy voltage drop, to produce good sparking when operating on the induction coil principle.

More particularly, the invention has for an object the provision of an ignition apparatus including a magnetizable core with primary and secondary coils thereon, breaker points controlling the primary coil and operating in timed relation with the engine, an energizing coil deriving current from the battery and creating magnetic 45 flux which is distributed to and from the core by engine-driven flux distributors, and a switching means in the magneto operable by remote control for directing battery current through the primary coil and the breaker points, during the starting period, and for disconnecting the battery from the primary coil at all other times to allow the 50 spark to be produced on the magneto principle by the changes in flow of magnetic flux effected in said core by the action of said flux distributors magnetized by said energizing coil.

Another and important object is to arrange the aforesaid switching means so as to effect disconnection of the energizing coil from the battery during operation of the apparatus on the induction coil principle, whereby the magnetization 60 of the core by the flow of battery current through the primary coil, is unopposed by flux produced by the energizing coil.

The invention has for another object the provision of a single and stationary energizing coil with laminated rotors or flux distributors, one on each side thereof and fixed to an engine driven shaft, and cooperating to direct flux to and from the core carrying the primary and secondary 65 coils. This arrangement contributes to the production of a compact, light weight unit, with the weight of rotating parts reduced to a minimum, and avoids not only the extra cost of slip rings necessary to conduct the battery current to a 70 rotating coil but the troubles experienced in op-

eration due to faulty contacts at such slip rings.

These and other objects will more particularly appear as the detailed description proceeds and will be pointed out in the appended claims.

The invention will be disclosed with reference 5 to the accompanying drawings, in which:

Fig. 1 is a central sectional elevational view of an ignition apparatus embodying the invention;

Fig. 2 is an end elevational view of the breaker 10 point mechanism;

Fig. 3 is a cross sectional view taken on the line 3—3 of Fig. 1;

Fig. 4 is a fragmentary top plan view, showing the ignition coils,—the cover therefor having been 15 removed;

Fig. 5 is a view, taken similarly to Fig. 4 except that the ignition coils and their core have been removed to reveal the pole pieces;

Fig. 6 is a cross sectional view taken on the line 20 6—6 of Fig. 1;

Fig. 7 is an end elevational view of the switch unit shown in Fig. 6;

Fig. 8 is a fragmentary cross sectional view 25 taken on the line 8—8 of Fig. 4; and

Fig. 9 is a diagrammatical view showing the various electrical units of the apparatus, with their connections and the complete ignition system formed thereby.

Referring to Fig. 1 of these drawings, the apparatus is contained in a casing 1, having a cylindrical bore 2 closed at one end by a head 3, in which a suitable anti-friction bearing 4 is mounted. A removable head 5, held to casing 1 by cap screws 6, closes the other end of bore 2 and has 35 mounted therein an anti-friction bearing 7. Rotatably mounted in these bearings is a shaft 8 adapted to be driven from the engine which the ignition apparatus serves, and usually from the cam shaft. This shaft 8 is made of magnetizable 40 metal. It passes centrally through the coil 9 of an electromagnet and forms a core therefor adapted to be magnetized by the coil when the latter is energized. Coil 9 is stationarily supported in the bore 2 intermediate the ends thereof. Shaft 8 has fixed to it in axially spaced relation two flux distributors 10 and 10', disposed one on each side of the energizing coil 9 of the electromagnet. As shown in Fig. 3, these flux distributors are of like construction but one is angularly spaced from the other. Each is made up of soft iron laminations (Fig. 1) held together as by rivets 11, and each includes a plurality (three in the form shown in Fig. 3) of arms radially projecting from the shaft. These radial 55 arms, in the form disclosed, are equally spaced around shaft 8. The members 10 and 10' are keyed to the shaft (Fig. 1) and each is also clamped in axial position against a shoulder 12 by a nut 13, threaded on the shaft. In the form 60 herein shown, each radial arm of the distributor 10' is angularly spaced from the corresponding arm of distributor 10 by an angle of 60 degrees.

These flux distributors are adapted to direct flux from the electromagnet to and from a core 65 14, made up of soft iron laminations, suitably held together as by rivets 14'. On this core are mounted primary and secondary coils 15 and 16, respectively. The distributors not only make and break a magnetic circuit through this core a plurality of times during each revolution of shaft 8 but, preferably also, effect this result by creating reversals of flux through the core, as will later appear. For these purposes the flux distributors cooperate with pole pieces made up of 70 75

soft iron laminations and suitably fixed in the casing 1 and in this instance embedded therein during the process of casting the casing. There are two pairs of these pole pieces (Fig. 5), one pair for each distributor, the members of one pair being marked 17 and 18 and the corresponding members of the other pair being marked 17' and 18', respectively. The pole pieces 17 and 18 lie in the same transverse plane as the distributor 10 (Fig. 1) and the pole pieces 17' and 18' lie in the same transverse plane as the distributor 10'. The casing 1 has a flat face 19, approximately tangential to the cylindrical portion thereof and through this face is an opening leading into bore 2 (Figs. 3 and 5). Each pole piece has one end formed with a flat face 20 lying in the plane of said flat face 19. The other end of each is formed with an arcuate surface 21 concentric with the shaft 8 and adapted to cooperate with the arcuate ends of its flux distributor. The pole pieces 17 and 17' are interconnected by a bridge 22 (Figs. 3 and 4), made up of soft iron laminations, suitably held together as by rivets 23. The pole pieces 18 and 18' are similarly connected by a similar bridge 24. The ends of each bridge rest directly on the flat faces 20 of the pole pieces. The core 14 interconnects the bridges 22 and 24 (Figs. 3 and 4) and its ends rest directly on top of the bridges 20 in seats provided for this purpose as shown in Figs. 1 and 3. Clamps 25, one at each end of core 14, are secured to casing 1 by screws 26 and act to press the core ends tightly against the bridges and the latter tightly against the faces 20 of the pole pieces.

The arms of each flux distributor and the pair of pole shoes, with which it cooperates, are so spaced that when one arm is covered to any substantial extent by one pole piece of a pair, the other arms are entirely out of covering relation with the other pole piece of the pair. And the two distributors are angularly spaced so that when one arm of one, as 10, is covered by a pole piece, as 18, one arm of the other, as 10', is covered by the opposite pole piece, as 17'. Thus, with the distributors positioned as described, flux will then flow from the distributor of north polarity, say 10, through pole piece 18 and bridge 24 to the right hand end (as viewed in Fig. 3) of core 14 and return from the opposite end of the core through bridge 22 and pole piece 17' to distributor 10'. Flux cannot at this time pass from pole piece 17 to distributor 10 nor from pole piece 18' to distributor 10'. On continued rotation of shaft 8, that arm of distributor 10 which was covered by pole piece 18 moves out of covered relation therewith and a succeeding arm becomes covered by pole piece 17 and the arm of distributor 10', which was covered by pole piece 17' moves ahead and becomes covered by pole piece 18'. Flux then flows from distributor 10 through pole piece 17 and bridge 22 to the left hand end of core 14 and returns from the opposite end of the core through bridge 24 and pole piece 18' to distributor 10'. Flux cannot then pass from pole piece 17' to distributor 10' nor from pole piece 18 to distributor 10. Thus, each arm of each distributor cooperates successively with its pair of pole pieces to establish magnetic flux in core 14 first in one direction and then in the opposite direction. Three times during each revolution of shaft 8, magnetic flux is established in one direction through core 14 and three times during each revolution flux is established in the opposite direction in core 14.

The result is that flux is built up in the core six times during each revolution but alternately in opposite directions so that the transition is from a maximum in one direction to a maximum in the other direction, whereby a large effective flux change can be utilized in the core to induce a current in the coils thereon. The reversal of flux in core 14, while important and preferred, is not essential to the broader features of the invention.

The arrangement described is suitable for a six cylinder engine in which the cam shaft, travelling at one-half the crankshaft speed, drives the shaft 8. It is contemplated that the arrangement may be varied to suit engines having a greater or less number of cylinders by varying the number of arms on the flux distributor and the angular extent of the arcuate surfaces 21 of the several pole pieces.

The casing 1 is, of course, made of non-magnetic metal, such as aluminum for example. Co-operating with the casing 1 to enclose the core 14 and coils 15 and 16, is a cap 27 of insulating material such as bakelite. This cap rests on the surface 19 of casing 1 and is secured there by screws 28. The cap 27 has mounted therein a metallic socket 29 to which one end of a high tension wire 30 is connected. This socket carries a contact finger 31 which presses against the high tension terminal 32 of the secondary coil 16. The other terminal of coil 16 is grounded in any suitable way.

A suitable breaker point mechanism (Fig. 2) is mounted on the outer face of head 3 and operated by a cam 34 mounted on the outer end of shaft 8. This cam is clamped against one end face of the rotatable race of ball bearing 4 by a screw 32, threaded into shaft 8, the head of the screw being received in the counter-bored end of the cam as shown. The stationary breaker point 33 is carried by a metallic bracket 34 fixed to head 3 and thereby grounded. The movable breaker point 35 is fixed to one end of an arm 36 of insulating material. This arm is pivoted intermediate its ends on a stud 37 fixed to head 3 and the other end of the arm serves as a follower to be engaged and moved by cam 34. A flat spring 38 is secured at one end to arm 36 in electrical contact with point 35 and at the other end by a screw 39' to a block 39 of insulation, fixed to head 3. This spring tends to hold the breaker points engaged and also to electrically connect the terminal 39' to the movable breaker point 35. The bracket 34 is pivoted on stud 37 but is normally held against turning on this pivot by a screw 40 which clamps the bracket to head 3. The bracket is slotted to receive screw 40 and the slot enables a limited degree of swinging movement of the bracket, when screw 40 is loosened, for the purpose of adjusting the breaker point 33 relatively to its companion breaker point 35. An eccentric stud 41, mounted to turn in head 3, engages in a slot in bracket 34, and when this stud is turned the bracket will be swung on its pivot. The cam 34, as shown, is of hexagonal cross sectional shape and its six projections successively engage and move the arm 36 and cause the breaker points to separate six times during each revolution of shaft 8. The breaker point mechanism is given merely as an illustrative example of one suitable form and any other suitable form may be used as desired.

On the outer face of head 3 and encompassing the breaker point mechanism described is a circular flange 42 (Fig. 2) on which is seated a dis-

tributer cap 43 (Fig. 1) of insulating material. Spring clips 44 (Fig. 2), each pivoted to and between a pair of lugs on flange 42, engage in recesses in cap 43 (Fig. 4) in the usual way and hold the cap to its seat on flange 42 against axial and turning movement. The cap (Fig. 1) has a circular series, six in this case, of contacts 45 each connected to an exterior binding screw 46. To the screws 46 are connected the high tension wires 47 leading to the spark plugs 5 of the engine (see Fig. 9). The case also carries a central terminal 48 to which the lead wire 30 from the secondary coil 16 is connected. This terminal on its inner end carries a spring pressed plunger 49 which engages the inner end of a conducting strip 50 mounted on the distributor brush arm 51. The brush arm, which is of insulating material, telescopes over the outer end of the breaker point cam 31 and has a projection 52 fitting in a recess in the cam to effect an operable driving engagement. The outer end of strip 50 is movable successively into close proximity to the contacts 45 and thus the high tension current is distributed in proper order to the several spark plugs 5.

Variations in the timing of the spark may be effected in any desired way. All that is necessary is to turn the breaker point mechanism relatively to its operating cam 31 and this may be done either by turning the casing 1 relatively to shaft 8 or by turning shaft 8 relatively to the casing. A timing adjustment of the breaker point mechanism results in a corresponding adjustment of the distributor because the distributor brush is fixed to the cam 31 and the distributor cap is fixed to the head 3 which carries the breaker points.

In Fig. 1, we have shown a cup-shaped casing 53, secured in abutting relation with the head 5, to casing 1 by the described screws 6. The casing 53 houses a centrifugal governor of well known form for advancing the shaft 8 relatively to the shaft which drives it,—in this case a shaft 54 mounted in a hub-like extension 55 of casing 53. Fixed to the inner end of shaft 54 is a member 56 to which are pivoted at diametrically opposite points on studs 57 two weights 58, which at relatively high speeds fly outwardly. Two pins 59 engaged one with each of these weights are fixed to a plate 60, secured as indicated to one end of shaft 8. The arrangement is such that as the weights 58 fly outwardly they turn shaft 8 ahead of shaft 54 and effect an automatic advance of the spark. It is not thought necessary to describe this device in detail as it is not in itself a feature of novelty and is mentioned herein simply to show that provision may be made for an automatic spark advance mechanism.

The hub 55 is intended to fit into the usual socket provided in the engine crankcase and is usually mounted therein for limited turning movement, whereby the casings 53 and 1 may be turned by any suitable means, automatically or otherwise, to secure variations in the timing of the spark. Either or both forms of spark advance means may be used as desired. Within the described socket is located one end of an engine driven shaft and the shaft 54 is shaped, as indicated, for a coupling engagement with such engine driven shaft, when hub 55 is inserted in said socket.

Referring to Fig. 6, the casing 1, at a point near the head 3, is built out at diametrically opposite locations into generally rectangular form, to provide two opposed chambers 62 and 63 of rectangular cross sectional shape, leading out-

wardly from bore 2. In the chamber 62 is mounted a suitable condenser 64 which in this case is of the cartridge type having screw threaded terminals 65 and 66 extending axially from opposite ends thereof. The terminal 65 passes through the lower wall of the chamber 62 and is held to such wall by a nut 61. The terminal 65 is thereby grounded to and the condenser supported from the casing 1.

Fixed by screws 68 to casing 1 is a strip 69 (Figs. 4 and 6) of insulating material extending parallel with but slightly below the surface 19. This strip has three binding posts 70, 71 and 72 thereon. The terminals of the primary coil 15 are connected by wires 73 and 74 (Fig. 4) to the posts 71 and 72, respectively. A wire 75 (Fig. 6) connects the insulated terminal 66 of the condenser to post 72 and a wire 76, extending through head 3, connects the terminal 39', and thus the insulated breaker point 35, to post 72.

The magnet coil 9 (Figs. 1 and 3) is mounted within a short cylindrical casing 77 of insulating material, including a cover 78. This casing has diametrically disposed lugs 79 (Figs. 1 and 3), projecting radially outward and engaged in grooves 80 formed in the bore 2 of casing 1 and paralleling the axis thereof. The casing 77 may thus slide in an axial direction in the casing 1 and the grooves 80 extend from the open end of bore 2 to a point about midway thereof. In the assembling operation, shaft 8 with the casing 77 loosely mounted thereon between the rotors, is slid into the bore 2 with the lugs 79 riding in grooves 80. After the rotor is in place the casing 77 is pushed in until the lugs 79 abut the ends of the grooves 80, as shown in Fig. 1, whereby the casing 77 will be properly located between the rotors and in position to be fastened in place. This casing 77 is fastened by cap screws 81 and 82 (Fig. 3) which extend through casing 1 at diametrically opposite points and thread into metallic inserts 83 (see also Fig. 8) molded in the casing. The terminals of the magnet coil 9 are connected one to each insert 83. The screws 81 and 82, which are insulated from casing 1 by washers 84, thus hold the casing 77 in place and also serve as terminals for the magnet coil.

The chamber 63 (Fig. 6) serves to house a control switch which is mounted on the inner face of a plate 86, secured by screws 87 to the casing 1 to close the outer end of the chamber. This switch is operated under remote control by an electromagnet, including a magnetic core 88, a magnet coil 89 thereon and an armature 90, pivoted to plate 86. This electromagnet is secured to a bracket 85 fixed to plate 86 by bolts 85'. One terminal of coil 89 is grounded to bracket 85 and the other is connected by a wire 90' to a terminal bolt 91 which passes through and is insulated from bracket 85 and plate 86. The armature actuates 60 through the intermediary of slideable push rods 92 of insulating material, two spring fingers 93 and 94 (Fig. 7) which are fixed to bracket 85 by the bolts 85' and which are insulated from the bracket as indicated. The finger 93 is normally engaged with a stationary and grounded contact 95 and becomes disengaged therefrom when the magnet coil 89 is energized. The finger 94 likewise normally engages a stationary and grounded contact 96 but, when it is moved on energization of the magnet coil 89, it not only becomes disengaged from contact 96 but also engaged with a contact 97, carried by a finger 97', fixed to bracket 85 by the terminal bolt 91 and insulated from the bracket as indicated. The finger 94 is connected 75

5 by a wire 98 to the described binding post 71 and thus to one terminal of the primary coil 15. The finger 93 is connected by a wire 99 to the binding post 70 and a wire 100 leads from this post to a terminal 101, mounted on and insulated from a plate 102 which is secured by screws 103 to casing 1 and closes the outer end of chamber 62. The terminal 101 is connected by an insulated conductor 104 (Fig. 4) outside the casing 1, to the 10 terminal 82 of the magnet coil 9.

10 The work accomplished by the switch unit just described, as well as the operation of the apparatus, will best be understood from the diagram in Fig. 9 which shows all the electrical elements 15 above described and their connections with other elements used in conjunction with the engine. In this figure M is the electric starting motor used for cranking the engine; S is the usual switch for the starting motor, which switch is normally 20 held open automatically and is closed by the operator only for short intervals. B is the storage battery, usually of six volts. One side of the battery is grounded and the other side is connected by a wire 106 to one terminal of switch S. The 25 other terminal of switch S is connected by a wire 107 to one side of motor M and the other side of motor M is grounded. The usual ignition switch is shown at I and one terminal of it is connected by a wire 108 to the ungrounded side of battery 30 B and the other terminal thereof is connected by a wire 109 to the terminal 81 of magnet 9. A wire 110 leads from wire 107 to the terminal 91 and thus to the magnet coil 89, whereby this coil will be energized from battery B when and only 35 when the starter switch is closed. The other electrical connections have already been described.

In operation, the operator proceeds in the same manner as is usual with battery ignition systems. That is, he closes the ignition switch I and then 40 presses on the starter switch S to close it and hold it closed until the engine has been started by motor M. The closing of the ignition switch in this case serves only to close a circuit through the magnet coil 9. This circuit is as follows:— 45 from battery B by wires 106 and 108 to and through switch I, thence by wire 109 to terminal 81 of coil 9, thence from coil terminal 82 by way of wire 104 to terminal 101 and by way of wire 100 to terminal 70, thence by wire 99 to switch finger 93 and contact 95, and by the ground back to the battery. The closing of the starter switch S serves, in addition to its usual and normal purpose, to establish the "starting" ignition circuit. It causes the energization of the magnet coil 89 55 and insures the deenergization of magnet 9. Current flows from wires 106, 107 and 110 to terminal 91 and thence by wire 89' to coil 89 and from the coil by way of the ground connection back to the battery. On energization of coil 89, the armature 90 is pulled in by the then magnetized core 88 and the fingers 93 and 94 are moved from their normal positions illustrated. Movement of finger 93 simply opens up the circuit to magnet 9. Movement of finger 94 first breaks the ground connection 60 of the primary coil 15 and then closes a circuit from the battery B through the primary coil. The primary coil 15 and the breaker points are included in series in a normal "running" circuit which may be traced as follows:—from the 65 fixed and grounded breaker point 33 to the movable breaker point 35, thence by spring 38 to terminal 39' and by way of wire 76, terminal 72, wire 74, to the primary coil 15, and thence by wire 73, terminal 71, wire 98, switch finger 94, and 70 contact 96 to the ground. The movement of fin-

ger 94 by the magnet 89 breaks the last named ground connection of the primary circuit and extends such circuit as follows:—through contact 97, finger 91' to terminal 91, thence by wires 110 and 107 to switch S, and thence by wire 106 to the battery B and to the ground. This is the "starting" circuit and exists only for the short intervals during which switch S is held depressed. At such times, current from battery B will flow through the primary coil 15 whenever the breaker points 33 and 35 are engaged. The coils 15 and 16 then function on the same principle as the usual battery ignition coil. And during this interval, the electromagnet 9 is deenergized so that no magnetic flux from that source will be present 15 in core 14, to interfere with the magnetization of the core by battery current flowing through the primary coil 15. However, the instant that switch S is released, magnet 89 is deenergized and the battery is cut off from the primary coil by 20 the disengagement of finger 94 from contact 91 and such finger immediately engages the contact 96 to reestablish the normal primary circuit. Also, finger 93 engages contact 95 and reestablishes the circuit from the battery through coil 9. 25 The apparatus then functions as a magneto,—the distributors 10 and 10' creating flux changes in core 14 and causing the generation of current in the windings 15 and 16. The same breaker points control both the starting and running circuits of 30 the apparatus.

In the operation of the apparatus as a magneto, flux from the electromagnetic source 9 is allowed to build up in core 14 under conditions as favorable as possible. That is, the primary circuit is 35 kept open for relatively long intervals to allow the flux to build up in the core without the opposing influence of a short circuited primary coil. The breaker points, in the form of apparatus herein disclosed, complete one cycle of operation in 40 one-sixth of a revolution of shaft 8 or in 60 degrees. During this interval, the breaker points are closed about two-thirds of the time and open only about one-third of the time. In Fig. 3, the flux distributors are shown in the positions which 45 they occupy at the moment the breaker points open. Flux will then build up in core 14, flowing from right to left, the circuit being from the nearly vertical distributor arm 10 through pole piece 18, bridge 24, core 14, bridge 22, pole piece 17' to 50 that distributor arm 10' which in Fig. 3 lies immediately to the left of the aforesaid arm 10. The breaker points remain open until these two arms 10 and 10' become completely covered by their respective pole pieces 18 and 17' and until these 55 arms start to leave such pole pieces. Then the breaker points close and the then short circuited primary coil tends to resist a change of flux in core 14. This condition continues until the aforesaid two arms 10 and 10' have moved far enough 60 away from the forward edges of their respective pole pieces to create substantial gaps, such as those shown at g and g' in the magnetic circuit. Then the breaker points again open and a sudden change of flux occurs in core 14. But this 65 change is not simply from a maximum to zero but from a maximum in one direction to zero and beyond to approach as near as possible to a maximum in the other direction. For at the time of the opening of the breaker points, the aforesaid 70 arm 10' has moved into partially covered relation with pole piece 18' while a succeeding arm 10 has moved into partially covered relation with the pole piece 17. Flux then flows from left to right in core 14 and thus in the opposite direc- 75

tion to the flow of flux previously established. Hence, in the magnetic change, a reversal of flux is secured. Such a flux change in core 14 is effected six times during each revolution of shaft 8 to produce an ignition spark in the usual manner. This gives the three sparks per revolution required for the six cylinder engine.

It should be particularly noted that the primary coil 15 is not the same as the primary coil used in the conventional battery ignition system, although it operates on the same principle during the interval when battery current is directed through it. The coil is primarily a magneto coil and has fewer turns of larger wire and much less resistance than the average primary of an induction coil. The coil 15 is purposely designed to produce good sparking at low engine speeds on the magneto principle of operation. While the usual primary of an induction coil could be used as the primary of the magneto, its resistance, which is usually about four times as great as that of coil 15, would be too great to allow good sparking to be produced when the engine is operating at low speeds, especially where as here, the flux distributors are rotating slower than the engine at half the speed of its crankshaft. Thus, the primary coil 15 is essentially a magneto primary and does not have the same characteristics as the primary of an induction coil. And due to this fact, an important advantage is secured. Because of the low resistance of coil 15 an adequate flow of current through it can be secured even with a partially depleted battery or with a non-depleted battery which is subjected to a heavy voltage drop due to an unusual starting load. As an illustrative example and without setting up limitations, the coil 15 may have a resistance such that it will draw six amperes at three volts or half the usual battery voltage. This is as great a current as the average primary of an induction coil would draw from the battery at six volts. Thus, the coil 15 is enabled to produce better ignition, under the unfavorable battery conditions named, than the conventional battery ignition system and under normal conditions it produces a better spark due to the heavier current flow, say 12 amperes. In this way, the problem of a good spark at starting, even under unfavorable conditions, has been solved and a better starting spark under all battery conditions is effected than in the conventional battery ignition system.

The use of such a heavy current flow would be fatal if the flow were continued for any great length of time. The heavy arcs produced at the breaker points and the consequent burning of them would soon destroy them. Therefore, it is imperative that the time during which such heavy currents flow across the breaker points, be reduced to the barest minimum. It cannot safely be left to the judgment of the operator when to change from battery ignition to magneto ignition. At best, he would needlessly prolong the interval during which the apparatus operates on the induction coil principle and a careless operator might forget to make the change with the result that the breaker points would soon be destroyed. Then the system would be condemned as unsuitable. Therefore, the provision of the automatic means for predetermining and limiting the times of operation on the induction coil principle is a most important factor and, it is believed, the key to success in the production of a commercially successful ignition apparatus of the type in which the induction coil principle and magneto principle are combined. Such automatic means,

controlled by the starter switch, insures the shortest possible time for heavy current to pass through the primary coil and breaker points; it minimizes the destructive effects on the breaker points; it reduces the drain on the battery; and it offers at the same time the simplest and easiest form of control, requiring no attention from the operator and no change other than running a wire, such as 110, from the starter switch to the terminal 91 of the ignition apparatus.

In fact, the apparatus requires no substantial change for its installation. If originally installed in the automobile, one puts the ignition unit in the place usually occupied by the timer and distributor unit. After that, the wire from the ignition switch 1 is led to the terminal 81 of the energizing coil 9 instead of to the usual ignition coil. The only additional wiring is the wire 110, above described.

The use of the ignition apparatus of this invention results in a smaller consumption of current in a given time than the conventional battery ignition system. A heavier current is used on starting but this heavy flow is only momentary, usually a matter of a few seconds. In normal running, current from the battery is used only to supply the energizing coil and this coil consumes very little current, say for example, one ampere. The average coil of the conventional battery ignition system draws from 5 to 6 amperes on starting and about 4½ amperes on medium engine speeds, dwindling to lesser values at the higher engine speeds with resulting loss in effectiveness of ignition. Of course, the current used for the energizing coil is a constant load during operation of the engine, whereas in the conventional battery ignition system, the current flows only while the breaker points are closed. But it is essential in a battery ignition system that the breaker points be closed as long as possible in order to get as much time as possible for the building up of flux and usually they are closed about 70% of the time. Therefore, there is a substantial saving in battery current through the use of this apparatus.

The invention effects a reduction in the wear on the breaker points over that resulting from the use of the conventional battery ignition system. In order for the induction coil of the last named system to produce a reasonably good low speed spark and a reasonably good high speed spark, it is necessary to pass a much higher current through it at medium speeds than would otherwise be necessary and than is used in the present apparatus. Consequently, the larger amount of current flowing across the breaker points during the intervals of medium engine speed operation, and these are usually the longer intervals of engine operation, results in more rapid burning of the breaker points and lessened length of life. Furthermore, the condenser which is employed to reduce arcing at the breaker points, cannot so effectively accomplish its intended purpose in the battery ignition system as in the magneto. A condenser designed to function well on high speeds will not function well on low speeds and vice versa. The difference in current flow under these two conditions is too great to allow one condenser to properly work under both conditions. But in magneto operation there is not such a wide differential and it is a fact that one condenser will function much more effectively throughout the speed range than in a battery ignition system, and this fact means lessened wear and longer life of the breaker points. While

the condenser does not function as well during periods of battery operation, these periods as above set forth, are purposely made exceedingly short so that the wear occurring from this cause

5 is so reduced as to be negligible.

The apparatus of this invention produces a better spark at high engine speeds. The more rapid the engine speed, the more rapid is the flux change produced by rotation of the distributors 10 and 10' and the rate of change of flux as well as the amount of change is a factor in the production of the spark. Then, the flux is built up in the core 14 under the most favorable conditions, viz., while the breaker points are open 15 and thus without the opposing choking influence of a short-circuited primary. With the conventional battery ignition system, time is an important factor in the establishment of flux in the core of the induction coil. Magnetization occurs 20 only when the breaker points are closed and builds up relatively slowly. Naturally, as the engine speed increases, less and less time is available for the building up of flux, wherefore the current falls off and poor sparking results. In 25 contradistinction to the practice employed in conventional battery ignition systems of keeping the breaker points closed as long as possible, the practice here is to keep them open as long as possible and close them only for short intervals to 30 hold the flux while a gap is created in the magnetic circuit preliminary to the ensuing break.

The apparatus is a compact, light weight unit, complete in itself and requiring only two wire connections to the battery, as above described. It 35 utilizes an energizing coil in place of the more expensive magnets of cobalt steel which would be necessary to use to secure a degree of compactness approaching that herein disclosed. But the use of the coil is important for the reason 40 that the action of the magnetic source can be discontinued during periods of induction coil operation so as not to interfere therewith, whereas the harmful action of permanent magnets at such periods cannot be so easily avoided. It is deemed 45 important that the coil 9 be stationary. Use of slip rings is avoided as well as their initial cost and the troubles in operation likely to arise from their use. The weight of the rotating parts is also reduced by not mounting the coil 9 on the shaft 8 50 and it is important to keep the weight of rotating parts as low as possible and reduce the wear on the moving parts. The pole piece arrangement, with the bridge pieces and the core which interconnects them, is important in that it enables 55 the use of flux distributors of simple and inexpensive form and of a form which can be made up of laminated soft iron stampings as is desired for their excellent magnetic qualities. Specially shaped and expensive forgings, which 60 are also less desirable because of their poorer magnetic qualities, are avoided.

The invention thus provides an improved ignition apparatus, characterized in that it is adapted to more efficiently utilize the battery current 65 and secure better ignition with a less consumption of current than in a conventional battery ignition system and characterized also in that it is capable of producing a better starting spark and a better spark at high speeds and a good 70 starting spark under unfavorable battery conditions where the said conventional system would fail. The invention also enables a reduction in the drain on the battery and in the wear on the breaker points to be effected over the aforesaid 75 system.

The features disclosed herein and relating to dual ignition, wherein the transition from one form to the other is automatically effected in coordination with the operation of the starter motor, are claimed in our above-named application filed June 15, 1935 under Serial No. 26,726. 5

The features disclosed herein relating to mag- neto construction, apart from dual ignition, form the subject-matter of and are claimed in our application filed October 11, 1935 under Serial No. 10 44,567.

What we claim is:

1. Ignition apparatus for an internal combustion engine, comprising, a soft iron core, primary and secondary coils on said core, an interrupter, 15 a circuit including said primary coil and interrupter and adapted to be opened and closed by the opening and closing of the interrupter, a battery, an electromagnet including a magnet core and a coil effective when energized to magnetize 20 the magnet core, a circuit including said battery and electromagnet coil, flux distributing members connected to the magnet core and driven by the engine, said interrupter being driven by the engine to periodically open and close the primary 25 circuit, said members cooperating with the first named core to establish flux through said primary coil during its open circuit intervals, and switch means for connecting said circuits together to cause battery current to be directed through the 30 primary coil during its closed circuit intervals and ignition sparks produced on the induction coil principle, said primary coil having a sufficiently low resistance to enable effective sparks to be produced by the action of said flux distrib- 35 40 45 50 55 60 65 70 75

2. Ignition apparatus for an internal combustion engine, comprising, a soft iron core, primary and secondary coils on said core, an interrupter, a circuit including said primary coil and interrupter and adapted to be opened and closed by the opening and closing of the interrupter, a battery, an electromagnet including a magnet core and a coil effective when energized to magnetize the magnet core, a circuit including said battery and electromagnet coil, flux distributing members connected to the magnet core and driven by the engine, said interrupter being driven by the engine to periodically open and close the primary circuit, said members cooperating with the first named core to establish flux through said primary coil during its open circuit intervals, and switch means for connecting said circuits together to cause battery current to be directed through the primary coil during its closed circuit intervals and ignition sparks produced on the induction coil principle, said primary coil having a sufficiently low resistance to enable effective sparks to be produced by the action of said flux distrib- 40 45 50 55 60 65 70 75

3. In combination, primary and secondary coils, a core therefor, a source of magnetic flux including an energizing coil, means for periodically directing magnetic flux from said source through said core, circuit breaking means periodically operable in timed relation with the first-named means, a normal circuit including said primary coil and circuit breaking means, a casing for all the aforesaid elements, a battery outside the casing, a circuit including said battery and energizing coil, a starting circuit including said battery in addition to the normal circuit, a switch within said casing for changing the normal circuit to the starting circuit and vice versa and normally positioned to establish the normal circuit, remote control means for moving said switch from its normal position to a position wherein said starting circuit is established, and means operable by said remote control means for interrupting the circuit of said energizing coil.

4. An ignition apparatus for internal combustion engines, comprising, a stationary soft iron core, primary and secondary coils on said core, a rotary and magnetizable shaft adapted to be driven from the engine, a stationary coil encompassing said shaft and effective when energized to magnetize the same, a battery in circuit with the magnetizing coil for energizing the same, soft iron flux distributors fixed to said shaft one on each side of the magnetizing coil and cooperating with said core to alternately make and break a magnetic circuit therethrough, cooperating and relatively movable breaker points, a normal circuit including said breaker points and primary winding and adapted to be opened and closed by the opening and closing of the breaker points, means driven from said shaft for operating said breaker points to open them when the magnetic circuit through the core is broken by the action

of said distributors and hold them open while the distributors establish flux in said core and then close them, and means including a switch for changing said normal primary circuit to include said battery whereby current therefrom may pass through the primary coil when the breaker points are closed to induce a current in said secondary coil. 5

5. An ignition apparatus for internal combustion engines, comprising, a stationary soft iron core, primary and secondary coils on said core, a rotary and magnetizable shaft adapted to be driven from the engine, a stationary coil encompassing said shaft and effective when energized to magnetize the same, a battery in circuit with the magnetizing coil for energizing the same, soft iron flux distributors fixed to said shaft one on each side of the magnetizing coil and cooperating with said core to alternately make and break a magnetic circuit therethrough, cooperating and 10 relatively movable breaker points, a normal circuit including said breaker points and primary winding and adapted to be opened and closed by the opening and closing of the breaker points, means driven from said shaft for operating said 15 breaker points to open them when the magnetic circuit through the core is broken by the action of said distributors and hold them open while the distributors establish flux in said core and then close them, and means including a switch for 20 interrupting the circuit of the magnetizing coil and changing said normal primary circuit to include said battery whereby current therefrom may pass through the primary coil when the 25 breaker points are closed to induce a current in said secondary coil. 30
